(57) **CLAIM**

The modified design for “computer mouse”, as shown and described.

DESCRIPTION

FIG. 1 is a first perspective view of the computer mouse.

FIG. 2 is a second perspective view of the computer mouse.

FIG. 3 is a left side view of the computer mouse.

FIG. 4 is a right side view of the computer mouse design.

FIG. 5 is a third perspective view of the computer mouse.

FIG. 6 is a fourth perspective view of the computer mouse.

FIG. 7 is a top view of the computer mouse; and,

FIG. 8 is a bottom view of the computer mouse.
